F. ZEMAN

CAR LOCK

Filed Jan. 26, 1922

INVENTOR
F. Zeman
BY
M. R. Baum
ATTORNEY

UNITED STATES PATENT OFFICE.

FRANK ZEMAN, OF LITTLE FALLS, MINNESOTA.

CAR LOCK.

Application filed January 26, 1922. Serial No. 531,841.

To all whom it may concern:

Be it known that I, FRANK ZEMAN, a citizen of the United States, residing at Little Falls, in the county of Morrison and State 5 of Minnesota, have invented certain new and useful Improvements in Car Locks, of which the following is a specification.

This invention relates to improvements in sliding door locks and has for its principal 10 object to provide a device designed particularly for use in holding the doors of freight cars closed and locked.

Another object of the invention resides in the provision of a device which is equally 15 adaptable for use on the ordinary type of folding or sliding doors used in building construction.

With these and other objects in view the invention consists in the novel construction, 20 combination and arrangement of parts which will be fully set forth in the following specification, claimed, and illustrated in the accompanying drawing, in which,

Figure 1 is a perspective view of a fragment of a freight car showing the lock in use,

Figure 2 is a side view of the lock showing the cover plate removed and illustrating the keeper in section,

Figure 3 is a sectional view taken on line 30 3-3 of Figure 2,

Figure 4 is a side view of Figure 3.

Referring to the drawings in detail the numeral 10 designates the lock casing comprising a base plate 11 formed along its marginal edges with flanges 12 having screw receiving openings therein for the reception of the screws 13 by means of which the cover plate 14 is secured in place. An end flange 15 connects the ends of the side flanges 12 and effectively closes one end of the casing 10 while the opposite end is open. The base plate 11 and cover plate 14 are each provided with projecting guides 16 between 40 which the free end of the locking hook operates.

Formed in the plates 11 and 14 respectively are openings 17 and 18 and pivotally mounted in the opening 17 is the trunnion 50 19 of a barrel 20 having radiating therefrom the operating cam 21. A rectangular exten-

sion 22 projects longitudinally from the barrel 20 and enters the opening 18 to a point in a plane with the outer side of the plate 14. Pivotally mounted at 23 between the plates 55 11 and 14 is the locking hook 24, the free end of which is operable between the guides 16 and is provided with an angular extension 25 forming a shoulder for engagement behind the keeper 26 which is secured to one of the door elements. In order to normally hold the hook member in locked position a leaf spring 27 is secured within the casing 10 and tends to urge the hook member upwardly.

To provide for holding the lock in open position against the tension of the spring 27, a notch is formed in the barrel for the reception of a spring pressed pawl 28 which is mounted to slide in an opening 29 formed 70 in the upper flange 12 directly above the barrel. An angular extension is formed on the lower end of the pawl 28 and is provided with a bevelled end 30 for engagement with the cam surface 31 formed on the end of the 75 key member 32 having a rectangular socket for the reception of the extension 22.

In operation the key is slipped over the end of the extension 22 and upon forcing the key into the lock it will be seen that the pawl 80 will be forced upwardly and out of the notch in the barrel so that the same will be free to swing upon its pivot 19 thereby moving the cam 21 out of engagement with the hook member 24 thus allowing the same to swing 85 on its pivot 23 and into locked position.

While in the foregoing there has been shown and described the preferred embodiment of this invention, it is to be understood that minor changes in the details of construction, combination and arrangement of parts may be made without departing from the spirit and scope of the invention as claimed.

What is claimed is:

A lock comprising a casing, open at one end, guides on the open end of the casing, a keeper adapted to fit between the guides, a locking hook pivoted within the casing, the free end of said hook being operable between 100 the guides and to enter the keeper, a barrel pivoted in the casing, said barrel having a

notch in its periphery, a rectangular extension on the barrel, a key for engaging the extension to rotate the barrel, a cam on the barrel for engaging and moving the hook 5 out of the keeper, a spring impelled detent normally engaging in the barrel notch whereby said cam is held against the hook when in

open position, means formed with said key for retracting said detent when the key is inserted, and yieldable means for urging the hook into locking position. 10

In witness whereof I affix my signature.

FRANK ZEMAN.
